UNITED STATES PATENT OFFICE.

JAMES HARVEY FOSTER, OF ERA, TEXAS.

STEAM-BOILER CLEANER.

SPECIFICATION forming part of Letters Patent No. 293,444, dated February 12, 1884.

Application filed June 27, 1883. (No model.)

To all whom it may concern:

Be it known that I, JAMES H. FOSTER, a citizen of the United States, residing at Era, in the county of Cook and State of Texas, have 5 invented certain new and useful Improvements in Steam-Boiler Cleaners; and I do declare the following to be a full, clear, and exact description of the invention, such as will enable others skilled in the art to which it appertains to 10 make and use the same, reference being had to the accompanying drawing, and to letters or figures of reference marked thereon, which form a part of this specification.

The figure of the drawing is a vertical sectional view of my device.

This invention has relation to means for 15 cleaning the mud or foam, or both, from steam-boilers; and it consists in the construction and novel arrangement of devices, as hereinafter 20 set forth.

In the accompanying drawing, the letter *a* designates a boiler having its water-line at *b*.

c represents a pipe extending the length of the boiler at the water-line, and connected to 25 the rear end of the boiler by a cup, *d*, having the bolt *e*. This end of the pipe is closed. In the under side of the pipe are made, at certain intervals apart, a number of small apertures, *g*, the aggregate area of all of these apertures being 30 equal to the area of the pipe-opening.

h indicates a bushing, which is connected to the threaded end *k* of the pipe, this in turn being connected to the nipple *e'*, and this to the

elbow *f*, to which the valve-seat *l*, containing the throttle-valve *z*, is connected. The waste-pipe *m* is connected to the valve-seat. A similar pipe, *c'*, also formed with under apertures and connected by a cup and its bolt to the rear end of the boiler, extends along the bottom thereof about half an inch from said 40 bottom. This pipe may have an independent waste-pipe and throttle-valve, but is usually connected to the valve-seat of a common throttle-valve, a three-way valve being provided to accommodate both the foam-pipe *c* and the 45 mud-pipe *c'*. When the throttle-valve is opened, the foam will be forced through the upper pipe, *c*, and the mud through the lower pipe, *c'*, cleaning the boiler in a few moments.

Having described this invention, what I 50 claim, and desire to secure by Letters Patent, is—

The combination, with a boiler, of the longitudinal cleaner-pipe having a series of under perforations, the aggregate area of which 55 is about equal to the area of the pipe-opening, the cup and bolt connecting the closed end of the pipe with the boiler end, and the throttle-valve and waste-pipe, substantially as specified.

In testimony whereof I affix my signature in presence of two witnesses.

JAMES HARVEY FOSTER.
